AIR CONTROL MEANS FOR RELOOPING MACHINES

Filed June 9, 1947

UNITED STATES PATENT OFFICE

2,492,008

AIR CONTROL MEANS FOR RELOOPING MACHINES

Walter O. Runcie, Lima, Peru

Application June 9, 1947, Serial No. 753,476

2 Claims. (Cl. 66—1.5)

1

This invention relates to air control means for pneumatic relooping apparatus for picking up dropped stitches in stockings or other knitted fabric and constitutes simplification and improvements over the means embodied in my prior U. S. Patents for relooping apparatus, Nos. 2,415,111 and 2,418,483, granted February 4, 1947, and April 8, 1947, respectively.

An object of this invention is to provide pneumatic relooping apparatus comprising a built-in sewing machine air pump interconnected with a relooping needle assembly by means of a flexible tube, with improved and simplified air control and regulating means, said means co-operating to ensure uniformity of the pulsating air impulses generated by the pump and faultless operation of the relooping needle.

Another object of this invention is to provide a small breather orifice in the wall of the pump cylinder at a point just above the upper extremity of the needle bar or piston of the pump, when the latter is at its lowest point of reciprocation or lower dead center. At this position of the needle bar, fluid communication is automatically established between the interior of the pump cylinder and the atmosphere. Therefore, at the end of the suction stroke or at the beginning of the compression stroke of the reciprocating needle bar or piston, the air pressure within the fluid operating space or circuit of the relooping apparatus is equal to the atmospheric pressure. A breathing action takes place through the orifice once during each cycle of operation of the reciprocating needle bar or piston, thereby ensuring a full cylinder of atmospheric air at the beginning of the compression stroke of the reciprocating piston, which in turn ensures uniformly generated air impulses by the pump and satisfactory operation of the relooping needle. The breather orifice also prevents the creation of a partial vacuum within the fluid operating circuit of the relooping apparatus during operation.

A further object of this invention is to provide a hollow cylindrical or annular oil retaining packing ring of felt or other suitable resilient material, which is inserted in an annular groove provided for its reception, within and near the lower end of the pump cylinder. This device ensures ample lubrication of the pump and also functions as an effective air seal.

A further object of this invention is to provide a relooping needle assembly in which the cubic capacity of its cylinder bears a definite relationship to the cubic capacity of the sewing machine air pump. To provide for adequate control and

2

regulation of the air actuating the relooping needle, the pump should have a capacity approximately twice as much as the capacity of the relooping needle assembly. This excess air pressure also compensates for any leakage of air that may occur within the fluid operating circuit from any cause.

A still further object of this invention is to provide an improved dual purpose, manually controlled air regulator of extremely simple construction, the operation of which requires a minimum of physical effort on the part of the operator. The device consists of an orifice in the head of the cylinder of the relooping needle assembly, its purpose being to establish fluid communication between the interior of the cylinder and the atmosphere. The outer wall of the orifice is countersunk to provide for finely regulating the stroke of the knitting needle, by simply varying the pressure of the thumb or other digit of the operator's hand, on the countersunk orifice. By allowing all the pulsating air generated by the pump to escape through the orifice into the atmosphere, by simply raising the thumb, the needle ceases to operate and by covering the orifice with the thumb, the needle again resumes its normal operation. It is therefore, not necessary to stop the operation of the air pump while operating the relooping needle, as is customary with the use of special electrically driven relooping machines. This dual purpose air regulator provides the means for (1) instantly starting and stopping the knitting needle by closing or opening communication between the interior of the cylinder of the relooping needle assembly and the atmosphere and (2) for finely regulating the length of stroke of the reciprocating knitting needle, by simply varying the pressure of a digit of the operator's hand on the countersunk orifice.

With the foregoing objects and others which may hereinafter appear, the invention consists of the novel construction, combination and arrangement of parts as will be more specifically referred to and illustrated in the accompanying drawings, wherein is shown an embodiment of the invention, but it is to be understood that changes, modifications and variations may be resorted to which fall within the scope of the invention as claimed.

In the drawings:

Figure 1 is a detail elevation, partly in section, of the head of a sewing machine with the cover removed therefrom, showing the built-in air pump inter-connected by means of a flexible tube

with a relooping needle assembly constructed according to an embodiment of this invention.

Figure 2 is a vertical elevation of the cylinder of the air pump, removed from the sewing machine, and shows the improved breather orifice forming a part of my invention.

Figure 3 is an enlarged fragmentary side elevation of the upper portion of the relooping needle assembly.

Figure 4 is an enlarged fragmentary front elevation, partly in section, of the upper portion of the relooping needle assembly, showing the dual control countersunk orifice of my invention and the manner in which it is operated by means of the thumb and index finger.

Figure 5 is a greatly enlarged fragmentary sectional elevation of a small portion of the head of the relooping needle assembly, showing in greater detail the dual air control countersunk orifice forming a part of my invention.

Referring to the drawings, the numeral 10 designates generally the head of a sewing machine of conventional construction, which carries the drive shaft 11. A plate 12 is secured to the shaft 11, and plate 12 has extended therefrom an eccentrically disposed crank pin 13 on which one end of a link 14 is rockably mounted. The opposite end of link 14 is also rockably mounted on a pin (not shown) extending rearwardly from a collar 15 which encircles and is adjustably secured to the needle bar 16. Needle bar 16 is vertically slidable in a lower bearing 17 formed as part of the head 10, and needle bar 16 is also slidable in a cylindrical sleeve 18 depending from an enlargement 19 formed as part of the upper portion of head 10. Sleeve 18 constitutes not only the guide for needle bar 16, but also constitutes an air pumping cylinder, and needle bar 16 constitutes not only a needle carrier, but also constitutes an air pumping piston. Sleeve 18 is counterbored at its upper end, as indicated by the numeral 20, to receive a tightly fitting plug 21, said plug providing an airtight seal to form the head of the cylinder of the pump. Plug 21, at its upper end, is provided with an integral nipple 22. The counterbore 20 in sleeve 18, extends a short distance below the lower extremity of plug 21, thereby providing an annular oil chamber 23 within the sleeve 18. Needle bar 16, is provided near its upper end with a pair of lubricating grooves 24. An annular groove 25, is provided within and near the lower end of sleeve 18 to receive an annular oil retaining felt ring 26, which co-operating with chamber 23 within sleeve 18 at the base of plug 21 and oil grooves 24 near the upper end of needle bar 16, provide triple means for ample lubrication and effective airtightness of the pump.

For simplicity of description, the needle bar 16 will hereinafter be referred to as piston 16 and sleeve 18 as cylinder 18. Needle bar 16, and sleeve 18 slightly modified, constitute the elements of the pump.

A small breather orifice 27 is provided in the wall of cylinder 18 with the object of periodically establishing fluid communication between the interior of the pump cylinder 18 and the atmosphere. This action occurs at the beginning of the compression stroke of the reciprocating piston 16, during every cycle of its operation. The reciprocating piston 16 and the breather orifice 27, constitute a simple automatic slide valve and provide the means of accurately regulating the pulsating air pressure generated by the pump, automatically and instantaneously. This simple

air control mechanism also prevents the formation of a partial vacuum within the fluid operating circuit of the relooping apparatus, thereby allowing the pump to generate a well regulated flow of pulsating air pressure.

Nipple 22 of cylinder 18 of the air pump, is inter-connected by means of the flexible tube 28 to nipple 29 of the relooping needle assembly 30, for operating said assembly by the pulsating air impulses generated by the pump. Nipple 29, forms an integral part of screw-plug 31, the latter engaging corresponding screw threads in the head of cylinder 32 of relooping needle assembly 30. The head of cylinder 32 is provided with a pair of diametrically opposed spaced concave faced discs 33a and 33b which are integral with cylinder 32. Concave faced discs 33a and 33b, provide the means for holding and manipulating the relooping needle assembly 30 between the thumb Y and the index finger Z respectively, of the operator, as shown in Figure 4. Within cylinder 32, slides a piston rod 34 which carries at its upper end, a cupped leather piston 35. The lower end of piston rod 34, has secured thereto a slide latch needle 36. Piston rod 34 which is hollow is free to slide longitudinally within cylindrical bearing 37, but is prevented from turning by the engagement of pin-screw 38 with slot 39 of piston rod 34. One end of a helical compression spring 40 engages the under side of cupped leather piston 35 within cylinder 32, and its opposite end engages the lower end wall of cylinder 32. A short helical bumper spring 41, is attached to the lower end of screw-plug 31, to cushion the piston rod 34 against shock on its return stroke.

An improved dual purpose air control orifice 42, is provided in the head of the relooping needle assembly 30, said orifice 42 being obliquely disposed relative to the head of cylinder 32, and extends from a point on the lower part of the concave faced disc 33a, through the head of cylinder 32, to a point within and near the upper end of said cylinder. The upper extremity of the wall of orifice 42, located at the lower part of the concave faced disc 33a, is countersunk as shown at 43. Orifice 42, provides the means for manually establishing fluid communication between the interior of cylinder 32 and the atmosphere, whereby the sliding latch knitting needle 36, may be instantly started or stopped while the air pump continues to operate. The operation of the knitting needle 36, is always under perfect control of the operator. The combination of the orifice 42 with its countersunk aperture 43, provides dual air control means (1) for finely regulating the length of stroke of the reciprocating knitting needle 36 and (2) for instantaneously starting and stopping the action of said needle.

In the use and operation of this invention, the sewing machine is set in motion by means of the usual foot treadle, or by means of an electric motor. Compressed air impulses are thereby generated by the reciprocation of piston 16 within cylinder 18 of the pump, said pulsating air impulses causing the piston rod 34 of the relooping needle assembly 30, to reciprocate in unison with the piston 16 of the pump. Co-operative action of the lubricating grooves 24 on piston 16, together with oil groove 23 and annular groove 25 with its oil retaining felt ring 26, within cylinder 18, provide ample and continuous lubrication for and effective airtightness of the pump. The breather orifice 27, provided in the wall of the cylinder 18, ensures automatic regulation and control of the pulsating air impulses generated by

the pump, because, at the end of the suction stroke, or at the beginning of the compression stroke of the reciprocating piston 16, communication is instantaneously and automatically established between the interior of the cylinder 18 and the atmosphere. Therefore, any tendency towards the building up of a partial vacuum within the fluid operating circuit is immediately nullified, and the circuit is automatically filled with atmospheric air at the beginning of each cycle of operation of the reciprocating piston 16.

Due to the fact that the capacity of the cylinder 32 of the relooping needle assembly 30 is approximately one half of the capacity of the cylinder 18 of the pump, sufficient pulsating air pressure in excess of that required for the normal operation of the relooping needle assembly 30, is generated by the pump, to ensure proper operation and allow of adequate control of the knitting needle 36.

The dual purpose manual air control and regulating means incorporated with the relooping needle assembly 30, provides the operator with the means for effortless control of the knitting needle 36. All controls, which include starting, stopping and regulating the length of stroke of the knitting needle 36, are effected simply by grasping the concave faced discs 33a and 33b of the relooping needle assembly 30, between the thumb Y and index finger Z respectively, as shown in Figure 4 of the drawings. Using the upper edge of concave faced disc 33a as a fulcrum X and the thumb Y as a lever, the countersunk orifice 42 is closed or opened by the ball of the thumb Y, to start or stop the action of the knitting needle 36. Regulation of the length of stroke of the knitting needle 36, is accomplished very simply, by varying the pressure of the thumb Y on the countersunk orifice 42, this action allows of fine regulation of the air that is permitted to escape from the interior of the cylinder 32 of the relooping needle assembly 30, through the countersunk orifice 42 into the atmosphere, because the pulsating air forces itself through the orifice 42, thence flares out between the thumb Y and the countersunk aperture 43 of orifice 42 at reduced velocity. As a result, variations in pressure of the thumb Y, causes variations in the length of stroke of the knitting needle 36.

It will thus be apparent that I have provided

a number of inter-dependent air control means to facilitate the operation of pneumatic relooping apparatus.

What I claim is:

- 5 1. A relooping needle assembly, comprising a cylinder, a piston slidable in said cylinder, a needle connected to and movable with said piston, a head on one end of said cylinder formed with a fluid passage axially thereof, and a pair 10 of supporting members carried by said head, said head having a lateral passage extending from the top end of said cylinder and terminating in one of said supporting members for communicating the interior of the cylinder with the atmosphere, the outer end of said passage at said one supporting member being countersunk, closing of said outer end of said lateral passage effecting maximum reciprocation of said piston, and complete opening of said lateral passage effecting stoppage of said piston.
- 15 2. In a relooping needle assembly, a cylinder, a piston slidable in said cylinder, a spring constantly urging said piston toward the inner end of said cylinder, and a pair of dished finger 20 grasping lugs carried by the inner end of said cylinder, a passage extending from said cylinder and through at least one lug for communicating said cylinder with the atmosphere, the outer end of said passage being countersunk and adapted 25 to be closed by a digit engaging thereover, complete removal of the digit from said passage effecting stoppage of said piston, and partial removal of the digit from said passage effecting reduced reciprocation of said piston.
- 30 35
